UNITED STATES PATENT OFFICE

GEORGE W. DOOLITTLE, OF KANSAS CITY, MISSOURI.

GRINDING-MILL.

SPECIFICATION forming part of Letters Patent No. 276,570, dated May 1, 1883.

Application filed September 4, 1882. (No model.)

To all whom it may concern:

Be it known that I, GEORGE W. DOOLITTLE, of Kansas City, in the county of Jackson and State of Missouri, have invented certain new and useful Improvements in Grinding-Mills; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention has relation to coal and grain mills, and has for its objects to grind coal into a comminuted state, to grind grain into any desired condition for food, and to grind compounds of chemicals, mineral or vegetable.

A further object is to produce a mill of great grinding capacity, which I accomplish by the aid of a weighted platform, the weight to be shifted to the point where the heaviest grinding is to be done. Common or ordinary material may be used for this purpose—such as scrap-iron, stone, earth, sand-bags, and other cheap and accessible material—which may be found in any location. Also, to overcome certain objections in other mills and to construct a mill that will be cheap in first cost, easy of repair, interchangeable in its parts, economical in the amount of power required to operate it, and of increased crushing and grinding power are further objects of my invention.

To these ends my invention consists in, first, the combination, in a grinding-mill, of the bed-plate, the revolving frame, a series of separate grinding-wheels having independent axles and separate bearings, and stirrups or frames for each of said wheels, whereby a circumferential, a rotating, a vertical, and a twisting or frictional motion is imparted to said wheels; second, the combination, in a grinding-mill, of a series of a separate grinding-wheels having independent axles, bearings therefor, and the stirrups or frames, with a series of adjustable springs and a weighted platform; third, the combination, with the separate grinding-wheels having independent axles, bearings therefor, and stirrups, of the revolving cleaning and agitating brush, the friction-wheel, and bed-plate, whereby the brush will remove material

adhering to the grinding-wheels and agitate the material on the bed-plate to prevent its packing; fourth, the combination, with the separate grinding-wheels described, the wheel-frames D D, and stirrups I I, of the driving-wheel frame having on its periphery a belt-bearing and a belt, the driving-power being imparted to the machine from the circumference; fifth, the combination, in a grinding-mill of the bed-plate, separate grinding-wheels, the revolving frame, the stationary shaft, transverse radial arms and ball-and-socket joint-connection between said arms and shaft, whereby the frame may automatically adapt itself to any irregular motion or elevation in its travel around the bed-plate; sixth, the combination, with the bed-plate and the revolving frame and hopper, said hopper being provided with crushing-teeth and a delivering-spout, of a stationary toothed cone suitably bolted to the bed-plate and the crushing-wheel, said hopper and spout being adapted to rotate around the stationary cone and break and evenly distribute the material to the crushing-wheel; seventh, the combination, in a grinding-mill, of a revolving wheel-frame, grinding-wheels, and an inverted rake, the back thereof having a beveled knife-edge, said inverted rake being attached to the wheel-frame near the hopper with a series of other rakes, and their spring-bows arranged to rake the entire bed of material radially and consecutively from the center to the circumference; eighth, the combination, in a grinding-mill, of the bed-plate, a screen and flap-valves with means for ejecting stones or other hard or extraneous matter from the bed-plate and from under the wheels, consisting of the scraper-rakes for throwing off said matter from the bed-plate upon the screen and the ejector for forcing it out through the flap-valves; ninth, the combination, with the wheel-frame D, stirrups I, and spring b, of a grinding-wheel F, the said stirrup being hinged at one end to permit the wheel to have vertical motion, the other end being free and provided with a cap for the spring.

Referring more particularly to the accompanying drawings, and to the letters of reference marked thereon, the same letters denoting like parts in all the figures, Figure 1 represents

a side elevation of my improved grinding-mill, partly in section, the feeding and crushing hopper and the sustaining ball-joint being in section and the driving gearing in elevation. The feeding-spout is also shown in this figure and the means for conveying off the ground product. Also, the discharge opening and valves are shown. Fig. 2 shows a plan view of the apparatus with the hopper removed. It will be observed in this figure that two of the series of wheels are composed of four instead of three wheels, as shown, the object being to break joints and grind the material that would partially escape grinding by passing between the joints of the other series of wheels if the joints were not broken. This figure further shows the driving-belt around the periphery of the revolving frame, said frame itself forming a pulley; also, a plan view of the motive-power gearing. It 20 also shows the rakes in nearly their normal position. Fig. 3 represents a perspective view of one of the four sets of grinding-wheels, clearly showing the relative positions of the wheels, one of them being the crusher. Behind the finishing-wheels in this figure will be seen the cleaning-brush, so arranged as to clean the adhering material from the wheels, and also agitate and loosen the material on the bed after the wheels have passed and in front of the next adjacent wheels. Fig. 4 shows a detached sectional view of a single wheel hung on its stirrup-bearings, each wheel having independent bearings. Fig. 5 shows an enlarged detached sectional view of one of the journal-bearings and its axle or arbor. This figure shows one of the bearing-springs which support the platform placed upon the rear end of the stirrup. (See Fig. 6.) Fig. 6 shows the frames or stirrups in which the individual 30 grinding-wheels work, clearly showing the bearings in which the wheels are hung and the hinged connection for the driving-wheel frame. Fig. 7 shows a detached view of the inverted rake, having a beveled or knife edge on its back for scraping the bed-plate, and it is adjustable radially to a greater or less angle. Fig. 8 shows 40 one of the raking and scraping devices by which the finest of the material is scraped a little nearer the periphery of the bed-plate, the coarser passing through the inverted fingers. The raking end of this device rakes, levels, and 45 partially distributes the material for the following grinding-wheel to pass over. Each of the smooth grinding-wheels is provided with one of these rake and scraper instruments. Fig. 9 is a perspective view of the rotary 50 cleaning and agitating brush, clearly showing its friction working wheel and its hanger. Fig. 10 is an enlarged view of the ejecting device for discharging stone or other hard foreign substances from the machine through flap-valves located at proper intervals around the frame. Fig. 11 represents a sectional plan view of the 60 central cone provided with stops for the purpose of preventing the broken material from being continuously carried around the cone.

Fig. 12 represents a rear view of a series of wheels, in perspective, clearly showing the frame resting on the springs, and also the agitating-brush arranged to be in contact with the grinding-wheels, and also the bed-plate. Fig. 13 shows an enlarged view, in perspective, of one of the stirrups, also showing the hinged end, the spring in position, and a scraper attached. 75

A is the revolving driving-wheel frame, made of any suitable material, and incased by a sheet-iron drum having on its periphery a bearing, B, for a driving-belt, C. Within this revolving frame A are wheel-frames D D, arranged at right angles to each other, as shown in Fig. 2. Within these frames D D are arranged two series of grinding-wheels, E E and F F, and at right angles thereto are two other series, G G and H H, all working in hinged stirrups I I. 80 All the wheels have independent bearings or journals a, and by reason of the hinges each stirrup and wheel can have an up-and-down movement independent of its fellows, so that when any one of the wheels meets an obstacle 85 in the shape of a stone or other hard substance it can readily ride over it without disturbing or disarranging any of its fellow wheels. The wheel-frames are securely fixed to the revolving frame A, so that the whole structure forms 90 one compact frame. J are hinges to which the stirrups are hung. These hinges are secured to the frame, which runs along the grinding-face of the wheels at nearly its axial line, and the other ends of the stirrups are sustained by 95 the wheel-arbors. b b are a series of springs, one or more to each wheel, having seats upon the opposite ends of the stirrups to those where the hinges are, and upon these springs rests 100 the opposite side of the wheel-frame D, which supports the weighted platform K by the wheel-arbors and their journals a. These springs b b vary in size and strength for the purpose of 105 varying the pressure on any particular wheel desired, and are capable of being shifted from one wheel to another as occasion may require. A set-screw, c, may be employed to throw the weight on any wheel by screwing it down upon the spring-seat, thus contracting the spring 110 which bears in proportion on that particular wheel, while the other springs are in their normal condition. 115

U is an ejecting device securely fastened to the revolving frame at its lower edge on the inside, just over the discharging-screen. This 120 device rotates with the frame, and there may be one or more. Its office is to eject stones or foreign substances not at the time intended to be ground, and operates as follows: Around the periphery of the frame I place at intervals 125 flap-valves V, which remain shut by their own weight. When the rakes O rotate around with the wheels they throw stones or other hard substances out toward the periphery, which fall onto the screen. These stones being too 130 large to pass through the screen, the ejector strikes them and forces them through the flap-

valves, and thus the mill is kept clear of such obstructions.

One or more of the wheels next the hopper may have roughened or serrated faces. In this case I show only one, the object being to further crush the material already partially crushed or broken in the "cracker" or "breaker." This rough-faced wheel is mounted in the same way as the others.

10 Centrally located between the wheel-frames is the cracking or breaking hopper L, composed of a stationary cone, d, and revolving wall e, both having teeth in the usual way. This cone d performs a double function—*i. e.*, that of a support for the revolving frame and a cracking apparatus. Mounted upon the cone d is a ball-joint, f, upon which the whole frame revolves. The cone d is rigidly secured to the bed-plate by legs g g and bearings or feet h h, 15 and to the revolving frame A by the arms i i, intermediately connected to the ball-joint upon which the frame-work revolves. The object of the ball-joint is to permit lateral, vertical, or tipping motion of the frame when any irregularity takes place upon the bed-plate, which would cause the tipping of the frame from one side to the other. Without this ball-joint the parts would be strained and finally yield and break. The ball-joint may be lubricated by any well-known means. At the base of the cone d, I arrange two or more stops, j j, between which the cracked material accumulates, so that when the spout revolving with the hopper registers with the openings between the stops the cracked material will be forced down the spout and under the crushing-wheel.

It will be observed that the bottom of the hopper has but one exit, and that an inclined 40 revolving spout, k, travels with the hopper, thus delivering the cracked material continuously in the pathway of the crushing-wheel M.

Between the crushing-wheel M, and also between the inner wheels next the hopper and their adjacent wheels, I interpose an apron or shield, l, of sheet-iron, the object being to prevent large particles of coal or other material from flying under the smooth grinding-wheels, which would materially interfere with smooth 45 and even grinding.

Behind the serrated faced crushing-wheel M, I arrange an inverted rake, N, having its fingers projecting upward, as heretofore referred to. The bow of this rake is a spring, m, 50 which will yield to irregularities on the surface of the bed-plate. The spring-bow m is secured to the side of the frame, and arranged to swivel to any angle from the center, presenting just as much of the face of the scraper as may be found necessary to throw the proper 55 quantity of material under the next wheel; but the most important function of this rake is to separate the larger particles of the material from the finer through the fingers, and deposit them on the surface in its rear for the crushing-wheel again to pass over. This op-

eration goes on until the material is fine enough to be thrown under the next smooth grinding-wheel.

When the position of the rake is to be 70 changed the set-screw n is unscrewed, when the rake may be set at any angle. The screw is then screwed down and the spring again is securely fastened. The other rakes, O, are similarly fastened and set, but differ in construction, inasmuch as they are scrapers and rakes, and perform their functions—*i. e.*, that of scraping the material up by one side and leveling by means of the other, each rake gradually drawing the material to the circumference of 80 the bed-plate and under each wheel consecutively until it is ground as fine as may be required. The other function of rake O is that it also separates the fine particles from the coarse by its upwardly-projecting fingers. 85

The operation of the mill is as follows: The power is imparted to driving-pulley P, which turns the cog-wheels Q R and belt-pulley S, and in turn the mill-frame A. The material is now put in the hopper and partially crushed 90 and broken. It then passes down the spout k, under the crushing-wheel M, whence it is scraped and raked under each wheel until ground fine enough to be discharged through the circumferential screen T. The inner wheel 95 turns nearly regular on its path without twisting or dragging. The second wheel slightly drags. The third of one series and the fourth of the other series twist and drag with a grinding frictional motion, grinding the material to 100 an impalpable powder. This grinding, twisting, or dragging motion performs an important function in the perfection of fine grinding, and completes what would otherwise be left unfinished. Should it be desirable to heat 10 the bed-plate, and therefore partially dry the material lying upon it, such heat may pass through flues v beneath the bed-plate. This heat may be waste heat from a chimney, or it 110 may be steam, hot air, &c., as may be preferred.

Having described my invention and the best means at present known to me of carrying the same into effect, I do not desire to be confined to the special means described, as my invention is capable of being expanded to wide limits in its various details without departing 115 from the principle thereof; but

What I claim to be new, and desire to secure by Letters Patent, is—

1. The combination, in a grinding-mill, of 120 the bed-plate, the revolving frame, a series of separate grinding-wheels having independent axles and separate bearings, and stirrups or frames for each of said wheels, whereby a circumferential, a rotating, a vertical, and a twisting or frictional motion is imparted to said wheels, substantially as described, and for the purpose set forth.

2. The combination, in a grinding-mill, of a series of separate grinding-wheels having independent axles, bearings therefor, and the stirrups or frames, with a series of adjustable

springs and a weighted platform, substantially as set forth and described.

3. The combination, with the separate grinding-wheels having independent axles, bearings therefor, and stirrups, of the revolving cleaning and agitating brush, the friction-wheel, and bed-plate, whereby the brush will remove material adhering to the grinding-wheels and agitate the material on the bed-plate to prevent its packing, substantially as described.

4. The combination, with the separate grinding-wheels described, the wheel-frames D D, and stirrups I I, of the driving-wheel frame, having on its periphery a belt-bearing and a belt, the driving-power being imparted to the machine from the circumference, as set forth and shown.

5. The combination, in a grinding-mill, of the bed-plate, separate grinding-wheels, the revolving frame, the stationary shaft, transverse radial arms and ball-and-socket joint connection between said arms and shaft, whereby the frame may automatically adapt itself to any irregular tilting motion or elevation in its travel around the bed-plate, as described.

6. The combination, with the bed-plate and the revolving frame and hopper, said hopper being provided with crushing-teeth and a delivering-spout, of a stationary toothed cone suitably bolted to the bed-plate, and the crushing-wheel, said hopper and spout being adapted to rotate around the stationary cone and brake and evenly distribute the material to the crushing-wheel, substantially as set forth.

7. The combination, in a grinding-mill, of a revolving-wheel frame, grinding-wheels, and an inverted rake, the back thereof having a beveled knife-edge, said inverted rake being attached to the wheel-frame near the hopper, with a series of other rakes and their spring bows arranged to rake the entire bed of material radially and consecutively from the center to the circumference, in the manner set forth.

8. The combination, in a grinding-mill, of the bed-plate, a screen, and flap-valves with means for ejecting stones or other hard or extraneous matter from the bed-plate and from under the wheels, consisting of the scraper-rakes for throwing off said matter from the bed-plate upon the screen and the ejector for forcing it out through the flap-valves, substantially as described.

9. The combination, with the wheel-frame D, stirrups, I, and spring b, of a grinding-wheel, F, the said stirrup being hinged at one end to permit the wheel to have vertical motion, the other end being free and provided with a cap for the spring, substantially as described.

In testimony that I claim the foregoing as my own I affix my signature in presence of two witnesses.

GEORGE W. DOOLITTLE.

Witnesses:

B. F. MORSELL,
O. E. DUFFY.
